METHOD OF AND APPARATUS FOR REENFORCING THE MARGINS OF PAPER

Otto Gerngross, Berlin-Grunewald, and Hellmuth Christ, Berlin-Niederschöneweide, Germany

Application January 5, 1931, Serial No. 506,706
In Germany March 3, 1928

18 Claims. (Cl. 93—1)

Our invention relates to improvements in the method of and apparatus for reenforcing the margins of paper or fabric, and more particularly in the method in which a strip of paper or similar reenforcing material is folded and applied to both sides of the margin of the paper or fabric for protecting the same from being torn at its margin.

One of the objects of the improvements is to provide an apparatus in which the strip of paper is correctly passed with the proper tension from a spool thereof to the mechanism for applying the same to the margin of the paper, and with this object in view our invention consists in providing braking means for the said strip of paper in connection with the means for supplying the same to the apparatus. The said braking means consist of a weighted body placed on the spool and controlling the unwinding thereof by friction caused by gravity. In addition brakes are provided which directly act on the strip of paper for putting the same under tension while applying the same to the paper.

Another object of the improvements is to provide a folding member supplying the strip of paper to the rollers pressing the same on the paper, the said folding member being movable so as to adapt itself to irregularities in the feeding, the quality, or the size of the strip of paper.

Another object of the improvements is to provide an apparatus in which means for pressing the folded strip onto the paper and means for applying a crease thereto are combined into a single tool, the said tool comprising one or two pairs of coaxial pressing rollers and a pair of indented and interengaging creasing disks located between the same.

Another object of the improvements is to provide means for stretching the pressed and creased sheet and strip after applying the same to the paper, and with this object in view our invention consists in providing a pair of pressing rollers at the rear of said pressing and creasing rollers, the circumferential velocity of the said pressing rollers being slightly greater than that of the pressing and creasing rollers.

Another object of the improvements is to construct the machine so that the reenforcing strip may be readily inserted between the said rollers, and with this object in view our invention consists in constructing the aforesaid folding member so that it may be rocked relatively to the direction of the movement of the paper and the strip at such an angle that when inserting the strip into the same the said strip is located later-

ally of the said rollers, the said rollers being adapted to be separated from one another for permitting the projecting end of the strip to be inserted between the same from the side thereof.

Another object of the improvements is to mount the blades for cutting the strip after applying the same to the paper on a member which may be readily removed from the apparatus, so that the said blades may be readily cleaned or exchanged.

Another object of the improvements is to provide a method in which the reenforcing strip is provided at its middle with a second narrow strip bent around the edge of the paper, the said narrow strip being made from a particularly strong material.

Finally an object of the improvements is to provide a method and an apparatus in which the reenforcing strip is applied to the margin of the paper so that it is safely connected therewith even if the paper is less adhesive, and with this object in view our invention consists in piercing the paper to be reenforced along its margin so that the glue or cement applied to the reenforcing strip passes through the punctures thus produced and glues the folds of the strip together.

For the purpose of explaining the invention several examples embodying the same have been shown in the accompanying drawings, in which the same reference characters have been used in all the views to indicate corresponding parts. In said drawings,

Fig. 1 is a top plan view of the apparatus,

Fig. 2 is an elevation thereof,

Fig. 3 is an elevation viewed from the right in Fig. 2,

Fig. 4 is a sectional elevation taken on the line 4—4 of Fig. 2,

Fig. 5 is a sectional elevation on an enlarged scale showing the pressing and creasing rollers,

Fig. 6 is a fragmentary elevation viewed from the left in Fig. 5,

Fig. 7 is a sectional elevation showing a modification of one of the creasing and pressing rollers,

Figs. 8 and 9 are end and side elevations on an enlarged scale showing the strip folding member,

Fig. 10 is a sectional plan view on an enlarged scale taken on the line 10—10 of Fig. 2,

Fig. 11 is a sectional elevation on an enlarged scale taken on the line 11—11 of Fig. 2,

Fig. 12 is a fragmentary elevation of the right hand part of the apparatus, the front plate of the casing enclosing the creasing and pressing rollers being removed,

Fig. 13 is a sectional elevation taken on the line 13—13 of Fig. 12, and

Fig. 14 is a fragmentary view showing a part of the sheet to be reenforced and showing a re-enforcing strip in course of being applied to its margin.

Fig. 15 is a fragmentary view showing partly in elevation and partly in vertical and axial section a pair of rollers that cooperate in finishing the reenforced sheet.

In the example shown in the drawings the apparatus for applying a reenforcing strip of paper or fabric to the margin or margins of a sheet of paper such as tracing paper comprises a base 14 in the form of an angle iron adapted to be clamped to a table or the like by means of screws 15, the said base being provided at its front side with a guide 16 for the margin of the sheet of paper. On a bracket 17 a spool 18 is rotatably mounted which has a reenforcing strip 86, 87 made from paper or fabric wound thereon. On the bracket 17 an arm 20 is rockingly mounted which carries a friction roller 21 and on a second bracket 22 a second roller 23 is mounted. To the right hand end of the base 14 a frame is secured which mainly consists of a front plate 24 secured to the base 14 by means of stay bolts 26, and a rear plate 25, and in which are mounted pressing and creasing or distorting rollers 27 and 28 and pressing and stretching rollers 29 and 30. Further, on the frame a device for cutting the strip is mounted which comprises a stationary blade 31 and a movable blade 32.

The guide 16 for the margin of the sheet to be reenforced comprises an angular rail having its margin 19 upturned to form a U-shaped guide, the said rail being fixed to the base 14 by screws. At a part of its length the upturned portion 19 of the rail is formed with a cut-out portion 19'. The rail extends from the left hand end of the base 14 to a point near the frame 24, 25.

The spool 18 is mounted on a vertical bolt 33 that stands integrally upon the bracket 17. To the bottom part of the said bolt a circular disk 35 is secured and the disk carries concentrically a ring 36. Upon this ring as an axle the spool 18 is rotatably mounted. Upon the spool 18 when in place a weighted body in the form of a comparatively thick circular disk 37 is placed. This disk is non-rotatable on the bolt 33. By the weight of the said disk 37 the spool 18 is pressed upon the disk 35, so that the spool 18 is frictionally held between the said disks and does not overrun when the strip is pulled therefrom.

After being taken from the spool 18 the strip is passed between the friction rollers 21 and 23. The arm 20 carrying the roller 21 is rockingly mounted on a pivot bolt 39, and it carries integrally an upwardly directed stud 40 from which an integral arm 41 extends. In this arm the roller 21 is rotatably mounted. Preferably the roller 21 is milled circumferentially to increase friction. A spring 42 is attached to the arm 20 for pressing the milled roller 21 towards the roller 23, which roller 23 is likewise milled at the portion engaging the reenforcing strip.

The roller 23 is rotatably mounted on a bolt 43 rising from the bracket 22. It rests below on a disk of friction-engendering material such as raw hide or vulcanite, a coiled spring 44 acting on the roller 23 from above for pressing the same into frictional engagement with the said disk of raw hide. The friction may be regulated by means of nuts 45 screwing on the top end of the bolt 43. The roller 23 is flanged at its top and

bottom ends to provide guides for the reenforcing strip.

The reenforcing strip coming from the brake rollers 21, 23 is passed through a folding device 46 which consists of a tapering mouthpiece made from sheet metal and having a U-shaped cross-section, the said mouthpiece having its edges turned inwardly as shown in Fig. 8. The mouthpiece is supported at its delivery end upon a stem 47 by means of which it is jointed to a bifurcated block 48 which constitutes the head of a pivot bolt 49. This pivot bolt stands vertically in and turns freely in its support in a bracket 50. Thus the mouthpiece is adapted to be turned about the vertical axis of the bolt 49, which axis intersects the mouthpiece near its delivery end, and in addition the mouthpiece is adapted to be rocked about a horizontal axis. Thus in the operation of the apparatus the mouthpiece automatically follows any irregularities in the size, structure, and the feed of the reenforcing strip, and further it may (when the machine is being made ready for operation) be rocked about its vertical axis at such an angle that the strip of paper passed therethrough will extend to one side of the frame 24, 25 and the parts mounted thereon, as is shown in Fig. 1 in dotted lines.

The plate 24 is secured to the base 14 by means of the stay bolts 26 and screws 51, and the plate 25 is fixed to the plate 24 by means of a spacing block 52, an arm 53 fixed thereto, and spacing sleeves 54 and screws 55.

The pressing and creasing rollers 27 and 28 are mounted on shafts 56 and 57. Roller 27 is secured to its shaft 56 and the shaft 56 is journaled directly in the frame; roller 28 is rotatably mounted upon its shaft 57 as an axle, and the shaft 57 is rigidly carried in the bifurcated arm of one of a pair of bell-crank levers 70, which levers 70 are directly pivoted in the frame. The minute structure of rolls 27 and 28 is shown in detail in Figs. 5 and 6. As is shown in the said figures the rollers are composed of each two circular disks 58 and 59 and a creasing disk 60 located between the same, the said creasing disk being formed peripherally with teeth adapted by intermeshing to distort or impress the reenforcing strip and the paper without actually piercing the same. As appears from Fig. 5, the diameter of the disk 60 at the bases of the teeth is smaller than the diameter of the disks 58 and 59, in order to permit the teeth of the two creasing disks to intermesh, and simultaneously to permit the disks 58 and 59 to press the reenforced margin of the paper between the same. Coaxially of the upper roller 27 a gear wheel 61 is mounted on the disk 59. The disks 58, 59, the disk 60 and the gear wheel 61 are held together by bolts 62 that extend through a flange 63 also upon the shaft 56. The disks 58, 59 and the disk 60 of the lower roller 28 are held together in a similar way. The upper disk 59 is milled circumferentially.

The roller 29 is secured to shaft 64 and the roller 30 is rotatable upon shaft 65 as an axle; the shaft 64 is journaled in the frame and the shaft 65 is rigidly carried in the bifurcated arm of the other of the two bell-crank levers 70. These rollers 29 and 30 are adapted for frictional engagement with the reenforcing strip and the paper. They are slightly larger in diameter than the rollers 27 and 28, so that the reenforcing strip and the paper are stretched between the sets of rollers 27, 28 and 29, 30. This is desirable for the reason that the paper is reduced in length 75

5 at its margin by the creasing operation, whereby the paper is crumpled. As appears from Fig. 10 the rollers 29 and 30 are made with portions of different diameters, to accommodate the portions of different thickness of strip and sheet. The roller 29 is provided with a gear wheel 66.

For driving the rollers 27 and 29 a gear wheel 67 is provided which is mounted on a rotary shaft 68 carrying a crank 69.

10 The lower rollers 28 and 30 are not directly mounted in the frame, but on bell crank levers 70 rockingly mounted on pivot bolts 71 set in the frame. The shafts 57 and 65 are secured to the horizontal arms of the said bell crank levers, and 15 the downwardly directed arms of the said bell crank levers are acted upon by a strong coiled spring 72 tending to force the rollers 28 and 30 upwardly and towards the rollers 27 and 29. The rollers 28 and 30 are adapted to be moved downwardly and away from the rollers 27 and 29 by 20 means of a plate 73 engaging the extended ends of shafts 57 and 65 and adapted to be forced downwardly by means of a lever 74 rockingly mounted on a pivot bolt 75 borne by the plate 24, 25 said lever carrying a cam 83 engaging in a slot of the said plate 73.

The stationary blade 31 is fixed to the bottom end of the block 52. At its top end the said block is formed with two arms 76 and 77 in bores of 30 which a stem 78 carrying a head 79 is guided. Between the arm 76 and a shoulder 80 of the stem 78 there is a coiled spring 81 which tends to force the stem 78 upwardly. To the bottom end of the stem 78 the blade 32 is fixed. The block 52 may be removed from the frames 24, 25 by removing the screws 51, 55.

In alignment with the cutting edge of the blade 31 a mark 82 is made in the surface of the base 40 40, the said mark indicating how far the sheet must be advanced through the apparatus for cutting the strip.

At the left hand end of the base plate 14 an apparatus for punching a series of holes along-side the margin of the sheet of paper is provided. 45 As shown, the said apparatus comprises a pair of interengaging piercing rollers 90 and 91 in position for engaging the margin of the sheet of paper and adapted to be rotated from the shaft 56 in a direction for feeding the paper. The flange of the lower roller 90 is formed with holes 50 55, and the upper roller 91 carries corresponding teeth 96 adapted to engage the said holes for piercing the sheet of paper. The lower roller is rotatably mounted on a pivot bolt 92 secured to the base plate 14, and it has a gear wheel 97 secured thereto. The upper roller is secured to a shaft 93 rotatably mounted on a bracket 94 secured to the base 14. To the said shaft a gear wheel 98 is secured which is in engagement with the gear wheel 97. Further, the said shaft carries a sprocket wheel 99 connected by a chain with a sprocket wheel 100 to a shaft 55.

The operation of the apparatus is as follows:

On the spool 18 a reenforcing strip is wound 60 one face of which has a suitable cement applied thereto. The cement is of such a character that it remains soft and plastic for a certain length of time while being on the spool, and that it dries gradually when the strip has been applied to the paper. The leading end of the strip is drawn 65 from the spool and passed between the friction rollers 21, 23, and it is inserted into the mouth-piece 46, the said mouthpiece being set in angular position as is shown in Fig. 1 in dotted lines. The 70 lower rollers 28 and 30 are pressed downwardly 75

5 by means of the lever 74, and the projecting end of the reenforcing strip is passed between the rollers 27, 29 and 28, 30, whereupon the lever 74 is released so that the reenforcing strip is clamped between the said rollers. The sheet of paper to be reenforced is placed on the base 14 with its margin passing through the guide 16 and between the punching rollers 90, 91. By turning the crank 69 the paper and strip are passed through the folding member 46 and thereafter 10 between the pressing and creasing rollers 27 and 28. The recess 19 shows whether or not the sheet of paper is fed in the proper position. By means of the interengaging indented disks 60, 60 the strip and the margin of the paper are 15 distorted, and simultaneously the strip is pressed on the paper by the rollers 58 and 59. By thus making one or more creases in the strip and in the paper or otherwise distorting the same while the strip is still soft and plastic the said parts 20 are perfectly bound together. When the strip and paper pass between the pressing rollers 29 and 30 the circumferential velocity of which is slightly greater than that of the rollers 27 and 28, they are stretched so that the contraction 25 caused by creasing is compensated and the sheet and strip leaving the apparatus are free of any marginal corrugations. When the rear edge of the sheet coincides with the mark 82 the stem 78 is pressed downwardly thus cutting the strip. 30

In Fig. 7 we have shown a modification in which the rollers 58, 59 and the disk 60 are made integral. As is shown in the said figure the end portions of the roller 27 located at opposite sides of the teeth 60' are provided with rings 101 and 102. Thus the strip and paper are clamped between the said rings and yet the indentations 60' are adapted to interengage. 35

As is shown in Fig. 14, to the reenforcing strip 86 a narrow strip 87 is applied which is not coated 40 with cement and which is to be folded around the edge of the paper to provide additional reenforcing means. The said strip 87 adheres to the strip 86. Preferably it is made from particularly strong paper or fabric. In lieu thereof we may 45 embed one or more threads in the cement.

The reenforcing strip elaborated as shown in Fig. 14 is peculiarly serviceable, and to such a strip the apparatus as shown is particularly adapted. By virtue of the narrow strip 87, increasing the overall thickness of the medial portion of the reenforcing strip, the reenforcing strip presents in this thickened medial portion opposite surfaces that are not in high degree adherent; and, in consequence, the reenforcing 50 strip wound upon the spool 18 may readily be withdrawn as machine operation progresses. Of the friction rollers 21 and 23 it will be remarked that, while the body of roller 23 is of relatively great length (vertical extent) and of sufficient 55 length to sustain the reenforcing strip throughout all of its width, the roller 21 is narrower. This roller 21 will, in case the reenforcing strip be of the elaborated form (Fig. 14), engage that side of the reenforcing strip to which the narrow 60 strip 87 has been applied; and, by virtue of its relatively small length, the roller 21 will immediately engage the outer surface of the narrow strip 87 only. The marginal portions of the reenforcing strip with exposed areas of adhesive 65 coating will not, therefore, be engaged by nor foul the roller 21.

By piercing the sheet along its margin as is shown at 88 the cement of the strip 86 passes through the holes 88 and the folds of the strip 70 75

86 are cemented to each other. Thus even such paper for example as oiled tracing paper (which is not very adhesive relatively to the glue applied to the strip) is properly reenforced. In some cases we use reenforcing strips which are different in color for indicating the subject matter printed or drawn on the sheets of paper for convenience in filing the same.

While in describing the invention reference has been made to particular examples embodying the same we wish it to be understood that our invention is not limited to the constructions shown in the drawings, and that various changes may be made in the general arrangement of the apparatus and the construction of its parts without departing from the invention. For example, our invention is not limited to a construction in which a strip of reenforcing paper is supplied which has a non-cemented strip applied thereto, or to a machine in which a pierced sheet of paper is reenforced, or in which the sheet of paper is pierced by mechanism such as the rollers 80, 81 mounted on the apparatus. In some cases we reenforce a sheet of paper which has not been pierced, or which has been pierced before being placed on the apparatus. Further, the invention is not limited to a construction in which a previously glued reenforcing strip is wound on the spool 18.

30 We claim:

1. The herein described method of reenforcing the margin of sheets of paper or fabric, which consists in piercing a sheet of paper or fabric along its margin and folding a cemented reenforcing strip around said margin and on the pierced portion thereof, and pressing the reenforcing strip to the paper.

2. The herein described apparatus for reenforcing the margin of a sheet of paper or fabric, comprising means for guiding a sheet, means for supplying a reenforcing strip alongside the margin of the sheet, comprising an end-flanged spool carrying a supply of reenforcing strip, a support for an end-flanged spool containing said strip, such support consisting of a rigid horizontally-extending disk and a rigid vertically-standing bolt, and a weighted plate adapted to be placed upon said bolt and to rest upon a spool previously placed upon said bolt, such rigid disk and weighted plate co-operating when a spool is in place between them as braking means therefore, means for folding said strip around the margin of the sheet, and means for uniting said strip to said sheet.

55 3. The herein described apparatus for reenforcing the margins of sheets of paper or fabric, comprising means for guiding a sheet, means for supplying a reenforcing strip alongside the margin of the sheet comprising a pair of rotary friction members adapted to have the strip passed between the same, means operative upon one of said friction members tending to restrain the otherwise free rotation thereof, yielding means operative upon one of said friction members tending to hold it in engagement with its companion member with the strip in place between them, means for folding said strip around the margin of the sheet, and means for uniting said strip to said sheet.

70 4. The herein described apparatus for reenforcing the margins of sheets of paper or fabric, comprising means for guiding a sheet, means for supplying a reenforcing strip alongside the margin of the sheet comprising a pair of rollers adapted to have a reenforcing strip passed be-

tween the same, adjustable braking means for one of said rollers, means for pressing said rollers toward each other, means for folding said strip around the margin of the sheet, and means for uniting said strip to said sheet.

5 5. The herein described apparatus for reenforcing the margins of sheets of paper or fabric, comprising means for guiding a sheet, means for supplying a reenforcing strip alongside the margin of the sheet, a member for folding said strip around the margin of said sheet loosely mounted for rocking transversely of the plane of said reenforcing strip supplied thereto, and means for uniting said strip to said sheet.

10 6. The herein described apparatus for reenforcing the margins of sheets of paper or fabric, comprising means for guiding a sheet, means for supplying a reenforcing strip alongside the margin of the sheet, a member for folding said strip around the margin of the said sheet loosely mounted for rocking transversely of the plane of 20 said reenforcing strip, the axis on which said member is rockable being located substantially at the delivery end of the said folding member, and means for uniting said strip to said sheet.

15 7. The herein described apparatus for reenforcing the margins of sheets of paper or fabric, comprising means for guiding a sheet, means for supplying a reenforcing strip alongside the margin of the sheet, a member for folding said strip around the margin of said sheet loosely mounted for rocking transversely of the plane of 25 said reenforcing strip, the axis on which said member is rockable being located substantially at the delivery end of the said folding member, and means for uniting said strip to said sheet.

30 8. The herein described apparatus for reenforcing the margins of sheets of paper or fabric, comprising a pair of rotary members constructed for distorting and compressing a sheet having a reenforcing strip folded around its margin and 40 each comprising a circular pressing surface and a concentric circular indented portion having its indentations cut inwardly beyond the circumference of said pressing surfaces, and means for supplying a sheet having a cemented reenforcing 45 strip folded around its margin to said pair of rotary members.

35 9. The herein described apparatus for reenforcing the margins of sheets of paper or fabric, comprising a pair of rotary members constructed 50 for distorting and compressing a sheet having a reenforcing strip folded around its margin and each comprising a pair of pressing disks and an indented disk disposed between said pressing disks and concentrically thereof and having the 55 indentations cut inwardly beyond the pressing surfaces of said pressing disks, and means for uniting said strip to said sheet.

10. The herein described apparatus for reenforcing the margins of sheets of paper or fabric, 60 comprising a pair of rotary members constructed for distorting and compressing a sheet having a reenforcing strip folded around its margin and each comprising a circular disk formed circumferentially with projecting teeth and a concentric surface and a ring on said concentric surface having a thickness smaller than the height of said teeth, and means for uniting said strip to said sheet.

70 11. The herein described apparatus for reenforcing the margins of sheets of paper, comprising a pair of rotary members constructed for distorting and compressing a sheet having a reenforcing strip folded around its margin, a pair 75 of pressing rollers in position for taking the said

strip and sheet from said distorting and compressing members and having a circumferential velocity slightly greater than that of said distorting and compressing members, and means for 5 passing a sheet having a reenforcing strip folded around its margin through said members and rollers.

12. The herein described apparatus for reenforcing the margins of sheets of paper, comprising 10 a frame, means mounted on said frame for compressing a sheet having a reenforcing strip folded around its margin, a block detachably fixed to said frame and separable from said compressing means, a cutting device comprising two 15 blades both mounted on said block for cutting the reenforcing strip, and means for passing a sheet having a reenforcing strip folded around its margin through said compressing means and said cutting means.

20 13. The herein described apparatus for reenforcing the margins of sheets of paper or fabric, comprising mechanism for piercing a sheet along its margin, means for folding a reenforcing strip around the said margin of said sheet, means for 25 pressing said reenforcing strip on said sheet, and means for passing said sheet with its margin through said piercing means and thereafter through said compressing means.

14. In apparatus for reenforcing the margin of 30 a sheet of paper or fabric, means for guiding a sheet, means for folding a reenforcing strip around the margin of said sheet and securing to the sheet such folded strip, such means including two pairs of rollers adapted successively to 35 engage the so guided sheet with the reenforcing strip folded thereon, means for yieldingly holding one roll of each pair to position of co-operation with its companion in engagement upon a sheet with reenforced margin, and a single means for shifting simultaneously the two yieldingly 40 held rollers away from co-operative position with their companion rollers.

15. Apparatus for reenforcing the margin of 45 a sheet of paper or fabric including a support, means for guiding a sheet, means for folding a reenforcing strip around the margin of the sheet, two pairs of rollers adapted successively to engage the reenforced margin of a guided sheet, one roll of each of said pairs being journaled 50 in said support and the other two rollers of the two pairs being severally mounted each in one of two levers pivoted in said support, resilient

means for swinging the levers and holding the rollers borne thereby to co-operative position with the companion rollers of the two pairs, and means for swinging the levers at will against the tension of the resilient means last named.

16. The herein described apparatus for reenforcing the margins of sheets of paper, comprising 10 a pair of co-operating pressing rollers having portions different in diameter and forming a pass of which a portion is of relatively great width and a portion of relatively small width, and means to supply to such roll-pass a sheet having a cemented reenforcing and thickness-increasing strip folded around its margin and leaving the sheet elsewhere of less thickness, such 15 portion of less thickness being supplied to the narrow portion of the roll-pass and the marginal portion of increased thickness being supplied to the wider portion of the roll-pass.

17. The method herein described of applying 20 to the margin of a sheet of paper or fabric a reenforcing strip which upon one side, and throughout a medial portion of its width on the other side, is non-adherent and which in its marginal portions on such other side is adherent, which 25 consists in engaging the strip yieldingly upon opposite non-adherent surfaces, drawing the so engaged strip forward and folding it upon the margin of the sheet to be reenforced and in so doing causing the adherent marginal surfaces 30 of the strip to come untouched to contact upon opposite surfaces of the sheet, and pressing the reenforcing strip to the sheet.

18. The herein described apparatus for reenforcing the margin of a sheet of paper or fabric, comprising 35 means for guiding a sheet, means for supplying alongside the margin of the sheet a reenforcing strip which throughout a medial portion of its width is non-adherent and which in its marginal portions carries on one side exposed 40 areas of adhesive coating, such means including a pair of friction rollers adapted to have the strip pass between them, one of said rollers being of a length as great as the width of the reenforcing strip and the other being of less length, corresponding to the width of the non-adherent medial portion of such reenforcing strip, means for 45 folding the said strip around the margin of the sheet, and means for uniting said strip to said sheet.

50
OTTO GERNGROSS.
HELLMUTH CHRIST.
